United States Patent Office.

T. M. RICHARDSON, OF STOCKTON, MAINE.

Letters Patent No. 96,964, dated November 16, 1869.

IMPROVEMENT IN STEERING-APPARATUS.

The Schedule referred to in these Letters Patent and making part of the same.

To all whom it may concern:

Be it known that I, T. M. RICHARDSON, of Stockton, in the county of Waldo, and State of Maine, have invented a new and valuable Improvement in Steering-Apparatus; and I do hereby declare that the following is a full, clear, and exact description of the construction and operation of the same, reference being had to the annexed drawings, making a part of this specification, and to the letters and figures of reference marked thereon.

Figure 1, of the drawings, is a top view of my invention.

Figure 2 is a front view of the same.

Figure 3 is a detached view, showing the mode of connecting the block and bolt by spring-links.

My invention relates to steering-apparatus, and consists, mainly, in the construction and novel arrangement of devices, whereby the effects of the contraction or extension of the tiller-ropes, caused by the condition of the atmosphere, are counteracted, and the evil consequences of sudden shocks of waves upon the rudder obviated.

The letter A of the drawings designates the rudder-head, to which is attached the tiller B, slotted, in the direction of its length, both horizontally and vertically, to admit of the free movement of the slide C within it.

D represents the wheel.

E, the barrel.

F, the stanchions.

G, G', H, H' are the blocks.

K represents a horizontal guide or slotted bar, in which moves the foot of a vertical pin, c', fixed to the slide C, thereby serving to keep the slide, and, consequently, the blocks and tiller-ropes, always in a direct line between the fixed bolts m and n.

The blocks G and H are attached to the bolts m and n, respectively, by double links, so arranged that the link to which the block is attached works on a spring, s, secured to and coiled around the link which is attached to the bolt.

To the other ends of the blocks G and H, the ends of the tiller-ropes a' are attached.

The tiller-ropes then passes through the blocks G' and H', linked to the loops formed in the ends of the slide C; then through the blocks G and H, and is then wound around the barrel E.

It is apparent that the effects of the contraction or extension of the tiller-ropes, from moisture, atmospheric influence, or whatever cause, are, within ordinary limits, entirely counteracted by the action of the coiled springs s s. Further, when the rudder of a vessel is turned so that it is not a prolongation of the line of her keel, as, for instance, when lying to in a gale, the sudden and violent shocks of the waves against the upper portion of the rudder are destructive to the parts of ordinary steering-apparatus, and are often the cause of accident to the helmsman. All such evil consequences are obviated by the use of the coiled springs s s, as above described.

What I claim as my invention, and desire to secure by Letters Patent, is—

The guide K, in combination with the pin c', slide C, springs s s, and tiller B, when constructed and arranged to operate as specified.

In testimony that I claim the above, I have hereunto subscribed my name, in the presence of two witnesses.

T. M. RICHARDSON.
